CLAIM

The ornamental design for an immersion blender, as shown and described.

DESCRIPTION

FIG. 1 is a perspective view of an immersion blender, showing the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a partially enlarged perspective detail view thereof, taken from FIG. 1.

The broken lines in the drawings show portions of the immersion blender and form no part of the claimed design. The dot-dash broken lines in FIGS. 1 and 8 are included to show the partially enlarged view only and form no part of the claimed design.
